US00D400511S

United States Patent [19]

Tepman

[11] Patent Number: Des. 400,511

[45] Date of Patent: **Nov. 3, 1998

[54] **MAGNET STRUCTURE FOR A CONICAL TARGET**

[75] Inventor: **Avi Tepman**, Cupertino, Calif.

[73] Assignee: **Applied Materials, Inc.**, Santa Clara, Calif.

[**] Term: **14 Years**

[21] Appl. No.: **52,010**

[22] Filed: **Mar. 21, 1996**

[51] LOC (6) Cl. **13-99**

[52] U.S. Cl. **D13/183**

[58] Field of Search D13/183; 335/209,
335/216, 302, 303, 304, 305, 306; 204/192.12,
